CLAIM

The ornamental design for a welding device enclosure, as shown and described.

DESCRIPTION

FIG. 1 is a front perspective view of the welding device enclosure showing our new design;

FIG. 2 is a rear perspective view of the welding device enclosure of FIG. 1;

FIG. 3 is a right side view of the welding device enclosure of FIG. 1;

FIG. 4 is a left side view of the welding device enclosure of FIG. 1;

FIG. 5 is a front view of the welding device enclosure of FIG. 1;

FIG. 6 is a rear view of the welding device enclosure of FIG. 1;

FIG. 7 is a top view of the welding device enclosure of FIG. 1; and,

FIG. 8 is a bottom view of the welding device enclosure of FIG. 1.

The broken lines in the drawings depict portions of the welding device enclosure that form no part of the claimed design.
